APPARATUS FOR SUPPLYING STRIP

Emmet R. Tyrrell, Youngstown, Ohio, assignor
to Fessler Machine Company, Sharon, Pa., a
corporation of Pennsylvania

Application February 18, 1941, Serial No. 379,446

16 Claims. (Cl. 80—32)

This invention relates to the metal strip handling art and more particularly to an improved apparatus for uncoiling strip from compact coils thereof as well as to an improved strip supplying set up involving the use of such improved apparatus.

In various strip processing and utilization lines operative speeds have been increased to such an extent that the uncoiling devices now commonly employed to feed the strip to the lines are inoperative to uncoil the strip at a rate equalling the capacity of the lines without damaging the strip or the devices. It is desirable that the strip uncoiling mechanism which supplies the strip to the various production or utilization machines and/or lines be capable of operating smoothly and at high speeds without danger of injury to the strip or the equipment involved and it is accordingly the primary object of the invention to provide an improved mechanism having these desirable characteristics. This improvement is accomplished in accordance with the present invention by employing an expandable mandrel which rotates about a rigidly fixed axis and which is operative to forcibly engage the inner periphery of the coil thereby concentrically supporting the coil during the uncoiling thereof. This support also prevents weaving and chattering of the coil and looping of the strip as it leaves the coil thereby substantially eliminating any possibility of damage to the side edges of the strip or any probability of surface cracks or checks appearing in the strip. The expansion of the mandrel is accomplished by power means under remote control and, in addition, controllable power means is provided to rotate the mandrel and consequently the coil held thereon. The latter means includes an overrunning clutch to allow the coil to be rotated at high speeds by tension effected in the strip by a rolling mill or other apparatus to which the strip is supplied.

A principal use to which strip uncoilers are put in the steel industry is the uncoiling of strip before the four high mills in the cold rolling of strip to supply the strip to such mills. In the reversing mill a tensioning mandrel or drum is positioned on either side of a single four high stand and the strip run back and forth, being coiled onto one drum while being uncoiled from the other drum and vice versa and during the rolling process, the tension in the strip before and after the mill as well as the roll pressure are accurately controlled to effect a desired result in the rolling operation. In the tandem mill, a plurality, normally four, of four high stands are 55

employed and the desired reduction is obtained in one pass through the mill. Under present practice, tension is effected in the strip between the succeeding stands by proper control of the speed of rotation of the rolls in the succeeding stands and tension in the strip as it leaves the last stand is effected by coiling the strip on a power driven mandrel. In either type of mill, a substantial portion of the reduction effected may

5 be attributed to the back tension placed in the strip before the strip enters the respective stands of rolls. Without back tension, the reduction is less while the power required on the rolls of the mills is greater.

15 Under the present practice in reversing mill operation, the strip is fed to the mill from an uncoiler from where the strip first extends over the adjacent tensioning mandrel, without necessarily being in engagement with such mandrel, thence through the rolls of the mill and is finally wound around the tensioning mandrel on the far side of the mill. Even though roll pressure and front tension be applied during this pass the reduction is slight, due to the absence of back tension. In accordance with my invention, I propose to apply back tension in the strip during this initial pass and this is accomplished by so constructing the uncoiler that the same

20 will have sufficient structural strength and an inherent retarding or breaking mechanism to effect the required back tension in the strip. Thus the efficiency of operation of the mill is materially increased which fact should become apparent when it is considered that the total

25 rolling process may consist of but six or eight passes through the mill and that by rendering one of the passes effective which heretofore has been substantially ineffective the total number of passes may be reduced or a correspondingly greater reduction may be effected in the same number of passes. Thus to make the same product the mill time may be reduced from five to ten per cent thereby effecting substantial economies in the operation of the mill.

30 45 In present tandem mill practice employing, for example, four stands, the operation of the first stand is inefficient due to the absence of sufficient back tension in the strip with relation to the stand and in normal cases the deficiency of reduction may amount to $\frac{1}{3}$ or more. By employing the uncoiling apparatus of my invention and the mill layout and practice taught herein to supply strip to the tandem mill it is possible to bring the efficiency of the first stand up to 100% of its capacity and it should be obvious that this

will substantially increase the overall economy of operation of the plant.

It is therefore a further object of the invention to provide an improved cold mill layout whereby the efficiency of practical operation of such mills will be materially increased.

Yet another object of the invention is the provision of an improved assembly for uncoiling and supplying strip to apparatus acting on said strip and to effect desired back tensioning in the strip as it enters the apparatus. Back tensioning is advantageous in rolling operations as explained above and similarly, but to a much less extent, in slitting and trimming lines, etc. For the purpose of accomplishing this object of the invention there is provided the combination of a strip uncoiler of special design and a roller leveler so constructed and arranged in relation to the uncoiler that in addition to the uncoiling and levelling or working functions of these elements controllable and adequate back tensioning in the strip supplied may be effected by retarding forces distributed between the leveler and uncoiler. In this manner the assembly is made capable of wide applicability and the assembled machine elements are utilized more fully and more efficiently than has heretofore been suggested.

These and other objects and advantages of the invention will become apparent from a consideration of the following detailed specification and the accompanying drawings wherein there is specifically disclosed a preferred embodiment of the apparatus of the invention and a teaching of a desired manner of use of the apparatus.

In the drawings:

Figure 1 is a front view of an apparatus constructed in accordance with the principles of the invention;

Figure 2 is a longitudinal sectional view through one of the expandible coil supporting and rotating chuck assemblies of the apparatus of Figure 1;

Figure 3 is a schematic representation of a tandem mill layout showing the manner in which the apparatus of the invention may be applied to such mill; and

Figure 4 is a schematic showing of a reversing mill utilizing the apparatus and teachings of the invention.

The apparatus, in its preferred and illustrated embodiment, includes a base 10 on which are slideably mounted for movement toward and away from each other a pair of pedestals 11 and 12 each of which is provided with a downwardly extending lug 13. Lugs 13 are in screw threaded engagement with screws 14 and 15 which are arranged to be rotated by a motor 16 and when motor 16 is energized for rotation in one direction the pedestals 11 and 12 simultaneously move toward each other and when motor 16 is reversed the pedestals move outwardly. Rotatably mounted on the inner end of each of the pedestals is an expandible chuck indicated generally by reference numeral 17 which chucks are operative to tightly grip and rotatably support a coil of strip shown in outline at 18. The apparatus consists also of a pair of pinch rolls 20 and a roller leveler comprising rolls 21 journaled in housings 23 and 24 which are fixed in relation to the base 10. Pinch rolls 20 and roller leveler rolls 21 are driven by motor 25 through speed reducer 26, an air operated clutch 27, a gear case 28, and couplings 29.

Referring to Figure 2 of the drawings the coil holding and rotating chucks 17 each consist of

a rotatable disk 31 having an integral hub 32 which is keyed to a hollow shaft 33 driven by a motor and speed reducing assembly 34 through a one-way or overrunning clutch 35. Disks 31 are provided with a cylindrical-shaped outer periphery 36 and three or more radially extending guide-ways 37 each of which is adapted to slideably receive a block 38 having an integral outwardly extending jaw 39. A radially extending threaded shaft 40 has screw threaded engagement with each of the blocks 38 and keyed to the inner end of each of the shafts 40 is a bevel gear 41 housed within the hollow hub 32. Journaled in the pedestal 12 and extending concentrically through the hollow shaft 33 is a shaft 42 carrying a bevel gear 43 in mesh with each of the three or more gears 41. Shaft 42 is driven by a combined motor and speed reducer assembly 45 through a magnetic clutch 46 and gears 47, 48, and 49.

Positioned centrally below the chucks 17 is a hydraulic lift cylinder 50 having a concaved plate 51 at its upper end to engage and lift a coil of strip into a position wherein the axis of the coil is substantially coincident with the axis of rotation of the chuck 17. The mechanism supported by pedestal 11 is identical with the mechanism described specifically in connection with Figure 2 with the exception that the power means 34, 35 to rotate the chuck is omitted. About the peripheral surface 36 of the disk 31 carried by pedestal 11 is a brake band 53 operated by an air cylinder 54 carried by the pedestal 11. Means, not shown, is attached to the pedestal to restrain rotative movement of the brake band 53.

In operation, with the chucks 17 spaced apart a coil 18 may be lowered into position between the chucks and on the lift 51 and by actuation of cylinder 50 the coil is brought into horizontal alignment with the chucks 17. By properly energizing motor 16 the pedestal 11 and 12 and consequently chucks 17 are moved toward each other with the jaws 39 entering in the center opening of the coil and the disks 31 brought into proximity with the side edges of the coil. The magnetic clutches 46 being in driving condition, upon energization of motors 45 the jaws 39 are caused to move radially outward into pressure engagement with the inner periphery of the coil to tightly hold the coil in concentric position about the axis of rotation of the jaws and disks. When this is accomplished clutches 46 are disengaged and then chucks 17 are free to rotate without altering the radial positions of the jaws 37 since shafts 40 and 42 rotate as a unit about the axis of shaft 33. By energizing motor 34 the chucks 17 and consequently the coil are rotated and upon such rotation the outer end of the strip may be threaded through pinch rolls 20 and the roller leveler rolls 21, these rolls being driven by the motor 25.

If, as shown in Figure 3, the strip is to be supplied to a tandem mill, the stands of which are shown schematically at 60 the strip is threaded through the rolling passes by rotation of rolls 21 or rolls of the mill itself and as it leaves the last stand it is attached to a coiling and tensioning mandrel or drum 61. When the strip is secured to drum 61 the clutch 27 is disengaged allowing rolls 20 and 21 to rotate freely and thereupon brake motor 54 is energized so that the brake 53 in combination with the friction encountered in the rotation of rolls 20 and

21 together with couplings 29 and gears housed in casing 28 and in the rotation of the chucks themselves will provide sufficient back tension in the strip rearwardly of the first mill stand to enable the first mill stand to operate at maximum efficiency. By properly adjusting the roll pressure, speed, and torque in each of the stands of the mill and by rotating drum 61 at a predetermined speed under proper torque the strip is reduced to its proper thickness in one pass through the mill. The overall efficiency of the mill is substantially increased to the extent indicated above by enabling a greater reduction to be effected by the first stand of the mill.

Referring now to Figure 4 which illustrates the invention as applied to a reversing mill having a single stand 62, there is shown a reversible coiling and tensioning drum 63 on either side of the stand. In practice, the strip is wound onto the drums 63 and passes through the stand 62 first in one direction and then in the other direction with the tractive and braking efforts exerted on the drums giving the desired front and back tension in the strip. In accordance with prior practice, in the first pass of the strip through the mill i. e. as the strip was taken off the coil, insufficient back tension was applied and consequently only a part of the usual reduction was effected in this first pass. In accordance with the present invention the pass plane of the roller leveler 21 of the uncoiling mechanism of the invention is so positioned that sufficient back tension may be effected in the first pass to enable increased reduction to be effected thereby. The uncoiling apparatus is operated in the manner indicated above and when the end of the strip is firmly affixed to the drum 63 on the far side of the stand 62 the mill may at once be operated at maximum efficiency. The overrunning clutch 35 and the disengagement of clutches 27 and 46 enable the coil to be unwound at a speed commensurate with the normal operating speeds of the mills involved.

It should now be apparent that I have provided an improved apparatus for uncoiling metal strip and an improved cold rolling mill layout utilizing such apparatus whereby the economy of operation of such mills may be materially enhanced. The operation of the expandable chuck 17 is such that the coil is held rigidly and automatically centered whereby the coil may be unwound at speeds considerably higher than is possible to obtain without damage to the apparatus or stock by present mechanisms designed for comparable uses. The uncoiling is accomplished smoothly without chattering of the coil or apparatus and without injury to the side edges or flat surfaces of the strip.

At normal operating speeds, the brake and other operative parts of the machine may be so adjusted that the strip will leave the coil along a natural curve spiralling outward from the coil in the manner explained in my co-pending application Ser. #328,685 filed April 9, 1940. As pointed out in the specification of said co-pending application this method of uncoiling prevents the formation of coil breaks which is of distinct advantage. Figures 3 and 4 indicate the relation of the expandable mandrel to the pinch rolls and it should be understood that the expandable mandrel may readily be substituted for the coil supporting mandrel in the machine illustrated in the aforesaid co-pending application.

The above specifically described embodiments

of the invention should be considered as illustrative only as obviously many changes may be made therein without departing from the spirit or scope of the invention. For example, although 5 the uncoiling apparatus of the invention is designed for and is particularly adaptable for supplying strip to the cold mill it should be apparent that it is equally adaptable to other general uses as, for example, the supplying of strip to a pickling line. Likewise many changes may be made in the details of construction of the specific apparatus illustrated without mitigating from the effectiveness of the apparatus when utilized in connection with the tandem and reversing mills 10 as indicated in Figures 3 and 4 respectively. Reference should therefore be had to the dependent claims in determining the scope of the invention.

What I claim is:

- 20 1. Apparatus for uncoiling metal strip comprising in combination a base, a pair of supports slideably mounted on said base for movement toward and away from each other, an expandable chuck rotatably mounted on each of said supports and adapted to engage the opposite ends of a coil of strip, said chucks comprising jaws adapted to be moved into pressure engagement with the inner periphery of said coil, power means on said supports to move said jaws into said pressure engagement, means to disconnect said power means from said jaws, power means including an overrunning clutch to rotate at least one of said chucks and consequently the coil held thereon, and means to brake the rotation of at least one of said chucks.
- 25 2. Apparatus for uncoiling metal strip comprising in combination a base, a pair of supports slideably mounted on said base for movement toward and away from each other, an expandable chuck rotatably mounted on each of said supports and adapted to engage the opposite ends of the coil of strip, each of said chucks comprising a rotatable member having a plurality of outwardly extending jaws slideably mounted thereon for radial movement, a radially extending shaft having screw-threaded engagement with each of said jaws, a bevel gear keyed to the inner end of each of said shafts, a shaft journaled for rotation about an axis coincident with the axis of rotation of said member, a bevel gear keyed to said last mentioned shaft and in mesh with said first mentioned bevel gears, means to rotate said last mentioned shaft whereby said jaws will be moved into pressure engagement 30 with the inner periphery of said coil, and means to disconnect said rotating means from said last mentioned shaft whereby said member and shafts will rotate in unison.
- 35 3. Apparatus according to claim 2 further including power means to rotate one of said chucks, said power means including an overrunning clutch.
- 40 4. Apparatus according to claim 2 further including power means to rotate at least one of said chucks, said means including an overrunning clutch, and controllable means to oppose the rotation of at least one of said chucks.
- 45 5. Apparatus for uncoiling metal strip comprising in combination an expandable mandrel for engaging the inner periphery of the coil of strip to hold the coil rigidly thereon, said mandrel being rotatable whereby said coil will rotate about its center of mass, a pair of pinch rolls positioned above and in front of said mandrel whereby the strip will be pulled from said

coil along the curve tangent to said coil, a roller leveler adjacent the strip leaving side of said pinch rolls, power means to rotate said pinch rolls and the rolls of said roller leveler, and a remotely controlled clutch to disengage said power means.

6. Apparatus according to claim 5 further including power means to rotate said expandable mandrel, said last mentioned power means, including an overrunning clutch.

7. Apparatus according to claim 5 further including the power means to rotate said mandrel, said last mentioned power means including an overrunning clutch, and a controllable brake to oppose rotation of said mandrel.

8. In combination with a metal rolling mill having a strip tensioning device positioned beyond its material leaving end, means to supply strip to said mill comprising a strip uncoiler having a roller leveler associated therewith and means to tightly grip the inner periphery of a coil of strip for rotation about its principal axis, means to drive said leveler, and means including the friction encountered in the rotation of the parts of said leveler and uncoiler to effect sufficient back tension in a strip as it enters the reducing roll stand to enable said stand of the mill to effect increased reduction in the thickness of the strip as the strip moves from said uncoiler through said stand.

9. Apparatus for uncoiling metal strip comprising in combination an expandable mandrel for engaging the inner periphery of the coil of strip to hold the coil rigidly thereon, said mandrel being rotatable whereby said coil will rotate about its center of mass, a pair of pinch rolls positioned above and in front of said mandrel whereby the strip will be pulled from said coil along the curve tangent to said coil, a roller leveler adjacent the strip leaving side of said pinch rolls, and power means to rotate said pinch rolls and the rolls of said roller leveler.

10. Apparatus for supplying strip to a strip rolling mill comprising in combination a rotatable and expandable mandrel to tightly grip the inner periphery of a coil of strip for holding said coil and rotating the same about its principal axis, means to oppose rotation of said mandrel, a roller leveler adapted to receive the strip as it spirals off the coil held on said mandrel, the operation of the apparatus being such that the friction encountered in the rotation of the parts of the leveler and uncoiler effects sufficient back tension in the strip as it enters the rolling mill to enable said mill to effect increased reduction in the thickness of the strip as the strip moves from the coil through the mill.

11. Apparatus according to claim 10 further including power means to rotate said mandrel, said means including an overrunning clutch.

12. Apparatus according to claim 10 further including power means to rotate the rolls of said roller leveler, and a clutch to disconnect said power means from said rolls.

13. Apparatus for uncoiling metal strip com-

prising in combination a base, a pair of supports slidably mounted on said base for movement toward and away from each other, an expandable chuck rotatably mounted on each of said supports and adapted to engage the opposite ends of a coil of strip, said chucks comprising jaws adapted to be moved into pressure engagement with the inner periphery of said coil, power means on said supports to move said jaws into said pressure engagement, means to disconnect the power means from said chucks, and separate power means to rotate at least one of said chucks.

14. Apparatus for uncoiling metal strip comprising in combination a base, a pair of supports slidably mounted on said base for movement toward and away from each other, an expandable chuck rotatably mounted on each of said supports and adapted to engage the opposite ends of the coil of strip, each of said chucks comprising a rotatable member having a plurality of outwardly extending jaws slidably mounted thereon for radial movement, a radially extending shaft having screw-threaded engagement with each of said jaws, a bevel gear keyed to the inner end of each of said shafts, a shaft journaled for rotation about an axis coincident with the axis of rotation of said member, a bevel gear keyed to said last mentioned shaft and in mesh with said first mentioned bevel gears, and means to rotate said last mentioned shaft whereby said jaws will be moved into pressure engagement with the inner periphery of said coil.

15. Apparatus for supplying metal strip to a device acting on said strip and to effect desired back tension on said strip comprising in combination a rotatable and expandable mandrel to tightly grip the inner periphery of a coil of strip for holding said coil and rotating the same about the principal axis thereof, means to oppose rotation of said mandrel, a roller leveler adapted to receive the strip as it spirals off the coil held on said mandrel, the operation of the apparatus being such that the friction encountered in the rotation of the parts of the leveller and the opposing force encountered in the rotation of said mandrel effects distributed back tension on the strip.

16. Apparatus for supplying metal strip to a device acting on said strip having means to pull said strip and for applying back tension in the strip intermediate said device and apparatus comprising in combination an expandable mandrel for engaging the inner periphery of a coil of strip to hold the coil rigidly thereon, said mandrel being rotatable whereby said coil will rotate about its principal axis, means comprising a roller leveler adapted to receive the strip as it leaves the coil on the mandrel, the rolls of said leveller and the opposing force encountered in the rotation of said mandrel effecting distributed back tension in said strip, and means to rotate said mandrel to facilitate threading through of the leading end portion of said strip.

EMMET R. TYRRELL.
